UNITED STATES PATENT OFFICE.

LEONARD L. RUGGLES, OF WHEATON, ILLINOIS, ASSIGNEE, BY MESNE ASSIGNMENTS, TO AUTOMATIC ELECTRIC INC., OF CHICAGO, ILLINOIS, A CORPORATION OF DELAWARE.

PARTY-LINE AUTOMATIC TELEPHONE SYSTEM.

Application filed August 14, 1925. Serial No. 50,191.

The present invention relates to party-line automatic telephone systems, and the broad general object is the provision of new and improved circuit arrangements whereby 5 a call for a party-line station that has been disconnected in a code-signalling party-line system may be extended to an intercepting operator.

Arrangements have been provided in the 10 past in connection with party-line automatic telephone systems in which the subscribers are selectively signalled for routing only those calls intended for party-line stations disconnected from the line to an intercepting operator. The arrangements provided for doing this have utilized, generally, selective apparatus which practically duplicates the signalling device at the disconnected station, which responds (only when a call is 15 extended to the line and intended for the disconnected station) to signal the intercepting operator. However, such arrangements cannot be applied to a code signalling system because in that system the only difference between 20 the signal for one station and the signal for another station is in the number of operations of the ringers on the called line or possibly in some instances in the length of time during which the ringers operate 25 continuously.

In order to provide arrangements for signalling the intercepting operator only on calls to disconnected stations in a code-ring- 30 ing party-line system, a selectively operable device has been provided for association with a line from which one or more stations has been disconnected. This device is operated simultaneously with the operation of the code selecting switch as the latter selects the 35 particular code according to which the called line is to be signalled. In this way the control of the extension of a connection to the intercepting operator is controlled by the same means that controls the operation of 40 the device that picks out the code according to which the called line is to be signalled, rather than being controlled selectively by the signalling current after it has been applied to the called line.

Another object of the invention may be 45 stated broadly to be the provision of a practical and economical arrangement of the intercepting equipment so that, when the service of the intercepting operator is required in 50 connection with a given station on a particu-

lar line, this service can be provided economically and without the necessity of providing a great number of selecting devices when only a few may be actually required at any one given time. The arrangement is such 60 that the number of devices required is no greater than the number of lines that may be simultaneously in the need of intercepting service. At the same time, the only changes that need to be made to switch a selecting device from one line to another is the mere changing of jumpers at a few points.

Referring now to the drawings, Fig. 1, shows the party line connector C having 70 access to 100 lines, one of which is shown. The connector C may be reached through first, second, and third selectors, or merely through first and second selectors, depending of course upon the size of the system of 75 which it forms a part.

The auxiliary code selector CS is associated with the connector C and it operates after the called line has been selected to select the particular code to be applied to the called 80 line in accordance with the station desired.

From a mechanical standpoint the connector C is a vertical and rotary switch in which the bank contacts are arranged in 10 horizontal rows or levels, with ten sets of 85 contacts in each level.

The code selector CS from a mechanical standpoint is a simple single-motion switch having the wipers 70 and 71 which are advanced in a forward direction by the stepping magnet 73 and which are released to their normal position by the release magnet 72, which is controlled by relay 8 of the connector C at armature 31, which relay is in turn controlled by the off-normal contacts 90 74 of the code selector CS.

The party line shown associated with the bank contacts 55-58 is provided with ten substations A-1-A-10, of which substations A-1 and A-10 are the only ones 100 shown. Five of the substation ringers are connected from one line conductor to ground and the other five ringers are connected between the other line conductor and ground. Accordingly, the application of ringing current to one line conductor affects five ringers and the application of ringing current to the other line conductor affects the other five ringers. The ringing current may be applied to either of the line conductors in any 110

one of five ways, consisting of from one ring to five rings.

Regarding the apparatus for producing the different codes, it may be pointed out that the distributor D, Fig. 1, energizes the relays 81—85, successively, and that these relays apply ringing current from the generator 89 to the conductors 76—80 according to the five codes desired, conductor 76 representing one ring and conductor 80 representing five rings. The particular code desired and the particular line conductor over which it is to be applied is determined by the setting of the code selector CS.

Regarding the equipment shown in Fig. 2, it will be noted that the line conductors and the private normal conductor corresponding to the line of the substations A—1—A—10 and also a fourth pulse conductor are extended to the left-hand contacts of the cross connect block CCB, one of these blocks being provided for each 100 line group. From the right-hand contacts of the cross connect block CCB there is a group of conductors 101 extending to the left-hand side of the intermediate distributing frame IDF. When the apparatus is installed a number of groups of conductors is run from the right-hand side of the cross connect block CCB to the left-hand side of the intermediate distributing frame IDF which is sufficiently large to take care of the maximum number of lines that it is calculated will require intercepting service simultaneously in the particular hundred-line group under consideration. This number may vary somewhat in different instances but it may for example be assumed to be fifteen groups per 100 lines. This arrangement will take care of providing intercepting service for fifteen lines simultaneously in any hundred line group.

Considering now the intermediate distributing frame IDF, the above mentioned groups of conductors terminate at the left-hand side of this intermediate distributing frame and when the occasion demands any one of these sets of conductors is cross connected in the manner of the set shown to an auxiliary switch AS which then becomes for the time individual to a particular line.

Regarding the number of the switches such as AS required, the number of these switches depends, not on the number of lines simultaneously requiring intercepting service in one hundred-line group, but on the total number of lines in the entire office that simultaneously require intercepting service, which, due to the well known law of averages, should in all cases fall far short of the total number required simultaneously in any hundred-line group multiplied by the number of such hundred-line groups.

It will be noted that the auxiliary selector AS is similar to the code selector CS. The switch AS carries a single wiper 110 which

selects any one of ten conductors according to its setting which extend from the associated bank to ten contacts on the associated cross-connect block CCB'. This cross-connect block is provided with an eleventh contact which may be connected to any one of the first ten by means of a jumper such as 111 to extend the connection through to the intercepting trunk IT only when the wiper 110 lands on the contact connected up by a jumper such as 111.

Since it would be uneconomical to provide a separate intercepting trunk for each of the auxiliary switches such as AS, arrangements have been provided whereby a single intercepting trunk such as IT may serve a great number of these auxiliary switches. That being the case, arrangements must be provided whereby two calls cannot be extended simultaneously to the same intercepting trunk. That result is accomplished by the relay group RG which is common to as many of the auxiliary selectors such as AS as are associated with the intercepting trunk IT. It is contemplated that two or three intercepting trunks can take care of the intercepting calls arising in a ten thousand line office, in which case the auxiliary selectors such as AS are divided into a corresponding number of separate and distinct groups with a relay group such as RG associated with each group of auxiliary selectors.

The manner in which the equipment shown operates will now be explained. For this purpose it will be assumed first that the subscriber at substation A—10 is called through the connector C.

When the connector C is seized through the trunk comprising conductors 14—16, line relay 2 pulls up over conductor 14 and 16 and closes at armature 18 a circuit for release relay 3. Release relay 3 applies ground at armature 20 to the release trunk conductor 15 so as to maintain the preceding switches operated; applies ground to the local locking conductor 63 at armature 19; and at armature 21 opens a point in the circuit of release magnet 11 and prepares a circuit for vertical magnet 12.

When the calling subscriber dials the next digit in the desired number, line relay 2 falls back a corresponding number of times and, upon each deenergization, it closes at armature 18 and its resting contact a circuit for vertical magnet 12, the circuit at the time of the first closure being as follows: from ground by way of armature 18 and its resting contact, armature 21 and its working contact, lower contact of off-normal spring 91 and said spring, series relay 4, and the vertical magnet 12 to battery. By the operation of vertical magnet 12 the wipers 51—54 are raised step by step until they stand opposite the desired level of bank contacts. Relay 4 is energized in series with vertical

magnet 12 on the first impulse of current delivered to the latter and maintains its armature attracted by virtue of its slow action. The off-normal springs are shifted 5 at or near the end of the first vertical stroke with the result that the last part of the first impulse to the vertical magnet as well as all the following impulses traverse a circuit path which includes the two lower off-normal 10 springs and armature 22 and its working contact.

At the end of the vertical movement, relay 4 falls back and at armature 22 opens a further point in its own circuit and that of 15 vertical magnet 12 and closes a point in the circuit of the rotary magnet 13.

When the calling subscriber dials the next digit in the desired number, line relay 3 falls back a number of times as before and 20 each time it falls back it closes a circuit for rotary magnet 13. The circuit of rotary magnet 13 is as follows: from ground by way of armature 18 and its resting contact, armature 21 and its working contact, the 25 two lower off-normal springs, armature 22 and its resting contact, resting contact and armature 32, armature 43 and its resting contact, and rotary magnet 13 to battery. By the operation of rotary magnet 13 the 30 wipers 51—54 are rotated into engagement with the bank contacts 55—58. Relay 9 is energized in multiple with rotary magnet 13 and it remains energized throughout the rotary movement by virtue of its slow acting 35 arrangement. At armature 35 relay 9 disconnects the test wiper 53 from the test winding of relay 10 and connects it instead through armature 42 and its resting contact to the busy relay 8, and at armature 37 40 shunts armature 32 and its resting contact so as to guard its own circuit and that of rotary magnet 13 at armature 32 in case busy relay 8 energizes during the rotary movement due to certain of the test contacts 45 encountered by test wiper 53 being grounded.

The operation at the end of the rotary movement depends upon whether the called line is busy or idle. If it is busy, busy relay 8 is energized and it remains energized until 50 the slow acting relay 9 falls back whereupon a locking circuit is closed at the normally closed contacts controlled by armature 35 and is as follows: from ground by way of the grounded release trunk conductor 15, armature 30 and its working contact normally closed contacts controlled by armature 35, and armature 42 and its resting contact to the busy relay 8. At armature 34, busy 55 relay 8 closes a circuit from the busy signalling conductor 75 through the resting contact and armature 45 and armature 34 and its working contact and the normally closed contacts controlled by armature 28 60 for applying the busy signalling tone to the lower talking conductor 16. The calling 65

subscriber, on hearing this busy signalling tone, is supposed to replace his receiver whereupon the connector C is released in the usual manner.

Assuming that the called line is idle at 70 the end of the rotary movement of the connector C, busy relay 8 is not energized and as soon as relay 9 falls back the upper winding of relay 10 is included in a circuit as follows: from ground by way of the grounded release trunk conductor 15, armature 30 and its resting contact, upper winding of switching relay 10, resting contact and armature 35, wiper 53, bank contact 57, relay 60, and magnet 62 to battery. Relays 10 and 60 75 pull up over this circuit but magnet 62 is not operated on account of the relatively high resistance of relay 60. Relay 60 does not operate fully and does not therefore connect up the associated wipers owing to 80 the usual mechanical interlocking device (not shown) between its armature proper and that of the associated line relay 61.

In the connector C, relay 10, upon energizing, locks its lower winding to the local conductor 63 at armature 41; opens a point 85 in the circuit of relay 8 at armature 42; prepares a circuit for pick-up relay 6 at armature 44; opens at armature 45 a point in the busy tone circuit; prepares an impulsing circuit to be later discussed at armature 39; and at armatures 38 and 46 connects up the wipers 51 and 54, at the same time placing direct ground on test wiper 53 at armature 40.

The calling subscriber now manipulates 90 his calling device in accordance with the digit 0 so as to bring the wipers 70 and 71 of the code selector CS into engagement with the tenth set of the associated bank contacts to apply the correct signalling current to the called line to signal the subscriber at 95 substation A—10. The ten impulses of current produced by the ten deenergizations of line relay 2 at this time are transmitted over the previously traced circuit to armature 43 of switching relay 10, but instead of going 100 through the resting contact of armature 43 to rotary magnet 13 these impulses are sent through the working contact of armature 43 to stepping magnet 73 of the counting switch CS. By the operation of stepping magnet 73 105 the wipers 70 and 71 are driven into engagement with the tenth set of associated bank contacts. The off-normal contacts 74 are 110 closed upon the first step of the wipers of the code selector CS and they close a point in the circuit of relay 8. This circuit is not completed right away on account of the fact that the slow acting relay 9 is energized by the impulses transmitted over the operating circuit, and this relay, being slow acting, 115 remains operated throughout the series of impulses.

When relay 9 falls back it completes at 120 armature 36 a circuit for relay 8. Relay 8 125

now energizes but it does not close a locking circuit for itself at this time owing to the fact that armature 42 is operated. Furthermore, the busy tone circuit is not completed 5 at armature 34 on account of the fact that armature 45 is operated. At armature 33 relay 8 prepares a circuit for pick-up relay 6. This circuit is completed as soon as the wiper 87 of the distributor D places ground 10 on the pick-up conductor 86, whereupon pick-up relay 6 energizes and locks itself to the grounded conductor 63 at armature 24, at the same time opening its initial circuit. At armatures 23 and 25 relay 6 extends the 15 wipers 51 and 53 of the connector through armatures 26 and 28 and their resting contacts to the wipers 70 and 71 of the counting switch CS. Ground through the upper winding of the ring-cut-off relay 7 is connected 20 through the tenth contact in the bank of wiper 70 to the said wiper 70 and then to wiper 51 of the connector C so as to provide a circuit for pulling up the ring-cut-off relay 7. The code conductor 80 is connected 25 through the tenth contact in the bank of wiper 71 and the said wiper and through armatures 25, 28 and 46 to the wiper 54 to supply ringing current to the lower talking conductor which is the one to which the 30 ringer of the substation A-10 is connected.

As the arm 87 moves over the contacts of the distributor D the relays 81-85 are consecutively energized with the result that ringing current from the generator 89 is supplied five times to the conductor 80 on each complete revolution of the wiper 87. The result is that all the ringers connected between the lower talking conductor of the called line and ground are operated five 35 times. The ringers which are connected between the other talking conductor and ground are not operated because the ringing current is not applied to that talking conductor. The various subscribers who hear 40 their ringers operating realize that the call is not for them with the exception of the subscriber at substation A-10 who, upon recognizing his code, answers the call by removing his receiver.

50 When the receiver is removed at substation A-10, a circuit is completed for ring-cut-off relay 7 as follows: from ground by way of ring-cut-off relay 7, tenth contact in the bank of wiper 70 and the said wiper, armatures 23, 26, and 38, wiper 51, bank contact 55, the called line, bank contact 58, wiper 54, armatures 46, 28, and 25, wiper 71, the tenth associated bank contact, and conductor 80 to battery either through the generator 89 or independent of the said generator, depending upon the position of the wiper 87 of the distributor D. Upon energizing, relay 7 locks its lower winding to the conductor 63 at armature 27, and at armatures 26 and 28 disconnects wipers 51 and 54

from the corresponding wipers of the code selector CS and connects them instead to the windings of the battery-feed impedance 5. Battery through the impedance 5 now flows out over the called line to energize the 70 transmitter and receiver at the substation A-10. The calling and called subscribers may now converse with each other in the usual manner. When the conversation is completed they both replace their receivers. 75

When the receiver is replaced at substation A-10 current merely ceases to flow over the associated line.

When the receiver is replaced at the calling substation, line relay 2 falls back and 80 opens the circuit of release relay 3 which falls back shortly thereafter and removes ground from the release trunk conductor 15 at armature 20, at the same time removing ground from conductor 63 at armature 19 85 and closing the release magnet circuit at armature 21. Responsive to the removal of the ground potential from local talking conductor 63, relays 6, 7, and 10 fall back, and responsive to the removal of ground from the release trunk conductor 15 the preceding 90 switches are released in the usual manner. Responsive to the closure of the release magnet circuit at armature 21, release magnet 11 energizes through armatures 18 and 21 95 and off-normal contacts 90 and restores the wipers 51-54 to their normal position, whereupon the release magnet circuit is opened at armature 90. As a further result of the deenergization of relay 3 it closes at 100 armature 20 a circuit through armature 31 and its working contact for release magnet 72 of the code selector CS. Release magnet 72 energizes and permits the wipers 70 and 71 to be restored to their normal position, whereupon the contacts 74 open and relay 8 deenergizes and opens at armature 31 the 105 circuit of release magnet 72. The entire connection is now released and the apparatus is ready to be used to set up another connection. 110

When the connector C is operated to call a station whose ringer is connected between the opposite side of the line to ground, for example, the substation A-1, the wipers 115 70 and 71 of the code selector CS are operated (after the connector C has been set on the called line) into engagement with one of the first five sets of bank contacts. In this case they are operated into engagement 120 with the first set of bank contacts because the substation A-1 is the one desired. Wiper 71 engages the first contact which associates the upper winding of the ring-cut-off relay 7 with the lower line conductor. Wiper 70 engages the first ringing conductor 125 76 with the result that when pick-up relay 6 subsequently operates as it does in the previously described manner a series of 130 rings takes place, one ring for each

rotation of the wiper 87 of the distributor D.

The subscriber at substation A-1 answers the call with results similar to those described hereinbefore.

Assuming now that the telephone service is discontinued at the premises of the subscriber at substation A-10, the attendant at the automatic exchange is informed of this fact and he connects the temporary jumpers shown on the cross-connecting block CCB with the result that the conductors 65-68 are connected with the corresponding cable conductors 101 leading to the intermediate distributing frame IDF. The attendant then connects jumpers on the IDF to connect the conductors 101 to the corresponding conductors of an idle auxiliary selector, for example, the auxiliary selector AS. The above operations associate the auxiliary selector AS with the party line, and in order to provide so that the intercepting operator will be signalled only when the subscriber at substation A-10 is called, the jumper 111 is connected between the contact associated with the common conductor 114 and the tenth contact in the bank of wiper 110, the tenth contact corresponding with the setting of the code selector CS, Fig. 1, when a call is intended for the subscriber at substation A-10. In this case when a call comes in for the subscriber at substation A-10 the stepping magnet 108 of the auxiliary selector AS is operated simultaneously with the operation of stepping magnet 73 of the code selector CS, the circuit of magnet 108 being as follows: from ground by way of the resting contact and armature 17 of line relay 2, armature 29 and its resting contact, armature 39 and its working contact of switching relay 10, wiper 52, bank contact 56, conductor 66, corresponding conductor of the group 101, corresponding jumper on the intermediate distributing frame IDF, lower winding of relay 102, magnet 108, common conductor 113, normally closed contacts controlled by armature 118, and relay 117 to battery. The lower winding of relay 102, as well as the winding of relay 117 is a low resisting winding with the result that magnet 108 operates through these two windings. By the operation of magnet 108 the wiper 110 is advanced step by step into engagement with the tenth associated bank contact. Relays 102 and 117 are energized in series with magnet 108 and, being slow acting, maintain their respective armatures attracted throughout the series of impulses. Relay 117 operates to place battery on conductor 114 so as to short circuit the lower winding of the guard relay 116 for a purpose to be pointed out later. Relay 102 opens at armature 106 a point in the circuit of release magnet 109 so as to prevent a premature operation of this magnet.

When wiper 110 lands on the tenth asso-

ciated bank contact, a circuit is closed from the grounded private normal conductor 67 through the path shown including the cross connect block CCB and the intermediate distributing frame IDF to armature 104 and 70 its working contact and thence by way of the upper winding of relay 102, wiper 110, the tenth associated bank contact, jumper 111, common conductor 114 and armature 119 and its working contact to battery. 75 Accordingly, relay 102 remains energized over this circuit instead of falling back responsive to the cessation of the series of impulses. That being the case, as soon as relay 117 falls back responsive to the termination 80 of the series of impulses it removes the shunt from around the lower winding of the common guard relay 116 with the result that relay 116 energizes and at armature 118 substitutes its high resistance upper winding 85 for the low resistance winding of relay 117 for a purpose to be explained later. As a further result of the energization of relay 102, the conductors 65 and 68 of the called line are extended at armatures 103 and 105 90 to the conductors of the intercepting trunk IT. That being the case, when the ringing current is applied to the called line the ringers of the substations A-6-A-9 are operated in the usual manner, the substation A-10 being disconnected in this case. At the same time, the ringing current passes over conductors 65 and 68 and through armatures 104 and 105 to the intercepting trunk IT. The ring-up relay 120 (at the 100 distant switchboard SB), whose lower winding is bridged across the conductors of the intercepting trunk IT through the associated condenser, energizes and closes a locking circuit for its upper winding at armature 121 and at armature 122 closes a circuit for the lamp 123.

When the intercepting operator notes the lighted condition of the lamp 123 she throws the key K so as to connect the listening taps 110 of her head set to the trunk. The upper contacts of the key K open the locking circuit of the upper winding of relay 120 whereupon relay 120 falls back and opens the circuit of the lamp 123 at armature 122. 115 A circuit for the ring-cut-off relay of the connector C is afforded by the operator's head set, whereupon relay 7 energizes and cuts off the ringing current in the hereinbefore described manner.

The operator now converses with the calling subscriber and informs him that the service has been discontinued at the called substation, after which the operator may restore her key K.

When the calling subscriber replaces his receiver, the connector C and the remaining part of the operated switches are released in the manner hereinbefore described. In addition relay 102 falls back responsive to 130

6
the removal of ground from the private normal conductor 67, as does also the slow acting relay 116 which has been maintained operated in series with relay 102, and 5 stores the relay circuits to the position shown in the drawing. At armature 106 a circuit is closed through contacts 107 for release magnet 109 which energizes and restores wiper 110 to its normal position, whereupon 10 the circuit of the release magnet is opened at off-normal contacts 107.

Considering the guarding arrangement provided, it will be noted that with relay 116 energized, as it is as long as the connection 15 remains established between the calling line and the intercepting operator, the magnets of the auxiliary switches such as AS cannot be operated over the common conductor 113 at this time owing to the high 20 resistance of the upper winding of relay 116, conductor 113 is connected to the upper winding of relay 116 at armature 118 at this time instead of being left open so that in case the existing call is cleared out during 25 the impulsive period of another call to a line equipped for intercepting service relay 116 will remain energized through its upper winding until the impulsive period is completed. This is done because it is better to 30 prevent a switch similar to AS from operating at all than to permit it to operate incorrectly as would be the case in case the operating circuit through common conductor 113 were restored in the middle of an 35 impulse period.

Regarding the utility of the arrangement 40 for maintaining the lower winding of the guard relay 116 short circuited until the end of the series of impulses that operates relay 45 117, the utility of this arrangement is two fold. It is useful where there are two or more subscribers disconnected from the line in which case two or more of the contacts in the bank or the wiper 110 are connected by means of jumper such as 111 to the common conductor 114. In this case the short 50 circuiting arrangement prevents the premature energization of relay 116 when the first bank contact is encountered that is connected to conductor 114 when the subscriber called is one corresponding to one of the following contacts in the bank of the switch. It will be readily seen that if relay 116 were 55 permitted to energize when the first contact is reached it would prevent a further advance of the switch AS.

Regarding the other utility for the short 60 circuiting arrangement, it may be pointed out that it will inevitably happen that occasionally a second switch similar to AS will start to operate before the first switch has finished its operation. In this case if the first switch were permitted to complete its operation and disconnect conductor 113 65 from its battery supply through the low

wound relay 117 the operation of the second auxiliary selector would be stopped oft-times before its completion. It is considered to be better practice to permit the operation of the second auxiliary selector to be completed 70 than it is to terminate the operation before its completion. Of course as soon as the second switch has completed its operation relay 117 falls back and relay 116 responds by pulling up in the hereinbefore described 75 manner.

It will be seen of course that it is possible that two calls may be extended to the intercepting trunk IT simultaneously but it is thought that this occurrence is so rare that 80 it may be overlooked.

What is claimed is:

1. In a telephone system, a connector switch having wipers, a party line accessible to said wipers, a first party-selecting switch 85 individual to said connector, a second party-selecting switch individual to said line, a line relay for said connector, a magnet controlled by said line relay to bring the wipers into engagement with said party line, means in said first party-selecting switch responsive to a subsequent operation of said line relay for selecting the desired party on the called line, and means in said second party-line selecting switch also responsive to said 90 subsequent operation of said line relay for selecting the desired station on the called line.

2. In a telephone system, a party line, a switch individual to such line having positions corresponding respectively to the parties on said line, means for extending a connection to said line, a plurality of signalling means corresponding respectively to the parties on said line, means controlled 10 subsequent to the selection of the called line for selecting the signalling means corresponding to the desired party, and means responsive to the same control for operating the switch on the called line to the position 10 corresponding to the called party.

3. In a telephone system, a party line, a switch individual to such line having a plurality of positions corresponding respectively to the parties on the associated line, means 11 for extending a connection to said line, and means controlled over said connection for operating said switch to a position corresponding to the desired party.

4. In a telephone system, connector switches mounted in groups, groups of party lines accessible to said connector groups, respectively, a plurality of party-selecting switches mounted in a single group, an intermediate distributing frame, connections 11 from each of said party-selecting switches to said distributing frame, and separate cables extending from said frame to each of said groups of connectors.

5. In a telephone system, a plurality of 11

party lines, means for providing intercepting service for one party on a party line, said means including contacts individual to each party line, an intermediate distributing frame, connections between contacts of the lines for which intercepting service is to be provided and the intermediate distributing frame, party selecting switches, individual connections at the intermediate distributing frame between the last mentioned party lines and the switches, and a jumper individual to each party selecting switch connecting a contact corresponding to the party to whom intercepting service is to be given with a common conductor.

6. In a party-line telephone system in which certain party lines are provided with individual party-selecting switches to complete the connection to an intercepting trunk line, a connecting relay individual to each party-selecting switch for connecting the associated line to the intercepting trunk line, and a circuit for said relay closed or not by the wiper of the switch depending upon the position in which the wiper is set.

7. In a party-line telephone system in which party lines are provided with individual party selecting switches set by impulses to complete connections to an intercepting trunk line, a release magnet for each individual switch, a slow acting relay energized during the setting of the switch to close points in the connection to the intercepting trunk and to maintain the circuit of said release magnet open, and another circuit for said relay completed through a wiper of said switch to maintain said relay energized after said impulses have ceased.

8. In a party-line telephone system in which certain party lines are provided with individual party selecting switches to complete connections to an intercepting trunk line, an operating magnet for each of said switches, a current supply circuit common to all of said operating magnets, and means responsive to the setting of one of said switches for opening said current supply circuit.

9. In a party-line telephone system in which certain party lines are provided with individual party selecting switches to complete connections to an intercepting trunk line, an operating magnet for each of said switches, a current supply circuit common to all of said operating magnets, means responsive to the setting of one of said switches for opening said current supply circuit, and means controlled over said common circuit for preventing the operation of the last named means during the setting of one of said switches.

10. In a party-line telephone system in which certain party lines are provided with individual party selecting switches to complete connections to an intercepting trunk

line, an operating magnet for each of said switches, a current supply circuit common to all of said operating magnets, means responsive to the setting of one of said switches for opening said current supply circuit, means effective upon the restoration of the last named switch for again completing said current supply circuit, and means effective in case an attempt is being made to operate another one of said switches at the time said release takes place to prevent the reclosure of said circuit until such attempt is terminated.

11. In a party line telephone system, a party line, a connector having access to said line via a single set of contacts, means associated with said connector for signalling any desired station according to a distinctive code, an intercepting trunk, and means effective in case the desired station is out of service for extending the call to said trunk.

12. In a party line telephone system, a party line, means for extending a connection to said line and for signalling a desired station thereon, and means including a switch individual to said line for extending the call to an operator in case any desired station is out of service.

13. In a party line telephone system, a party line, a connector having access to said line via a single set of contacts, means associated with said connector for signalling any desired station according to a distinctive code, an intercepting trunk, and directly operated means effective in case the desired station is out of service for extending the call to said trunk.

14. In a party line telephone system, a party line, a connector having access to said line via a single set of contacts, means for transmitting one of a number of distinctive codes over the line, means associated with the connector for selecting the code to be used in accordance with the station wanted, an intercepting trunk, and means operated simultaneously with said last named means for extending the call to said trunk in case the desired station is to be given intercepted service.

15. In a telephone system, a party line, means for extending a connection to said line, an operator's switchboard, means operative for predetermining which party on the line is to be called, and means operative into one of a plurality of positions simultaneously with said last named means for extending the call to the operator's switchboard under predetermined conditions.

16. In a telephone system, a party line, an operator's switchboard, means for extending calls to the line, and step-by-step means individual to the line for extending calls for certain of the parties on the line to the operator's switchboard.

17. In a telephone system, including a

party line and means for signalling a subscriber on the line, a branch extending from said line to a switching device, and means for conditioning said switching device so that it responds alike to extend the call to an operator's position when any of certain signals are used.

18. In a telephone system, a plurality of party lines, subscriber controlled means for selecting a desired line, subscriber controlled means effective to call a desired party on said line, a subscriber controlled device having a plurality of operative positions, one for each party on the line, for extending the call to an operator's position, and means for rendering the device effective when certain parties are called.

19. In an automatic telephone system, a plurality of party lines, automatically operated means for selecting a desired line, a switching device individual to each of said means, a switching device individual to each of said lines, means for directly operating both of said switching devices to any one of a plurality of positions, one of said switching devices being effective to apply signalling current of different characteristics to said line, and the other being effective from certain positions to extend a path for signalling current to an operator's switchboard over a branch of the line.

20. In a telephone system, a plurality of switching devices, means for individually directly operating any of said devices to any one of a plurality of positions, an electro-responsive mechanism, means for conditioning each device so that it will control the mechanism from any desired position of each device, means in said mechanism effective

when operated for preventing the initiation 40 into operation of any of the devices.

21. In a telephone system, wherein intercepted service is provided for certain party lines, an operator's switchboard, selecting devices connected to those lines requiring that service for connecting the lines to the switchboard, and means responsive to the setting up of one of said devices for opening the current supply through all of the other devices.

22. In a party line telephone system, in which certain party lines are provided with party selecting switches to complete connections to an intercepting operator's switchboard, means for operating each of said switches, a current supply circuit common to all of said means, means responsive to the setting of one of said switches for opening said current supply circuit, and means controlled over said common circuit for preventing the operation of the last named means during the operation of one of said switches.

23. In a telephone system, a plurality of party lines, means for code calling any desired party, a cross connecting frame, a branch extending from each line to the frame, an operator's switchboard, a plurality of switching devices connected to the frame, each of which may under predetermined 65 conditions extend a connection from the frame to the switchboard, and jumpers connecting certain lines with certain of the devices.

In witness whereof, I hereunto subscribe 75 my name this 11th day of August, A. D., 1925.

LEONARD L. RUGGLES.
